METHOD OF AND APPARATUS FOR
BLENDING PULP

Randolph V. Bingham, Portland, Oreg.

Application September 30, 1931
Serial No. 566,043

7 Claims. (Cl. 92—20)

This invention relates generally to paper making, and particularly to a method of and apparatus for blending pulp.

The main object of this invention is the provision of a method of and apparatus for blending pulp so as to provide complete uniformity throughout the contents of a pulp tank with regard to consistency, color and other physical and chemical properties which become factors in the process of making paper from the pulp in question.

This result is attained in the manner set forth in the specification following as illustrated in the accompanying drawings, in which:

15 Fig. 1 is a somewhat diagrammatic vertical section through the preferred form of pulp blender.

Fig. 2 is a transverse vertical section along the line 2—2 in Fig. 1.

20 Fig. 3 is a horizontal section along the line 3—3 in Fig. 1.

Fig. 4 is a plan of a modified form of tank.

Fig. 5 is a vertical section taken along the line 5—5 in Fig. 4.

25 Fig. 6 is a section through a modified form of the device.

Fig. 7 is a section taken along the line 7—7 in Fig. 6.

Fig. 8 is a diagrammatic view showing a still 30 further modification in which the pump inlet is branched.

Similar numbers of reference refer to similar parts throughout the several views.

Before entering into a detailed description of 35 this invention it will be understood that stock mixers and blenders of various types have been constructed in the past in which varying degrees of efficiency have been attained. The common faults residing in such devices consist in the fact 40 that they merely circulated in a continuous stream, thereby preventing a complete blending of the pulp in the various cooks which may occupy the mixing tank. Various means have been employed to accomplish this blending or mixing 45 operation, and these means have been either inefficient to secure the uniformity referred to, or were of a nature sufficiently violent to reduce the fiber length and thereby detract from the ultimate strength of the paper made from the 50 stock.

Where the agitator lacked the force to break down the fibers it required an undesirable amount of time and power for the blending action. My aim, therefore, has been to attain a complete 55 uniformity in all of the pulp in the tank in the

shortest possible time without detracting from the quality of the pulp itself, or using an unnecessary amount of power.

Referring in detail to Figs. 1 to 3 of the drawings, there is shown a horizontal cylindrical tank 10 supported in a saddle 11. Across the uprights 12 are mounted the horizontal supporting beams 13 on which are mounted the motors 14, 15, 16, 17 and 18 of pumps 14—A, 15—A, 16—A, 17—A, and 18—A whose inlets are near the bottom 65 29. The pump 14—A is nearest the inlet end 19, which is preferably provided with a rounded lower portion 20, as indicated. The inlet pipe 21, through which the stock enters the tank 10, is shown close to the end 19. The pump 18—A is 70 nearest the end 22, near the bottom of which is an outlet 23. The pumps 14—A to 18—A are each provided with an upwardly extending discharge pipe 24 to 28 respectively. The capacity of the various pumps is preferably equal, although not 75 necessarily so.

The pump 14—A has a discharge pipe 30 which discharges toward the end 19. The pump 15—A has a discharge pipe 31 which discharges toward the end 19. The pump 16—A has a discharge pipe 32 which discharges toward the end 19. The pump 17—A has an elongated discharge pipe 33 which also discharges toward the end 19, but quite close thereto, for reasons which will become apparent later. The pump 18—A 80 has a pair of discharge pipes 34 and 35, the former discharging toward the end 19 and the latter toward the end 22. Each of the discharge pipes 30, 31, 32, 34 and 35 is preferably branched 85 (as shown in Fig. 3).

The operation of the device is as follows: Assuming that one or more cooks of stock are admitted to the tank 10 by way of the inlet pipe 21, preferably bringing the level of the pulp in the neighborhood of the line 36, the pumps 14—A 90 to 18—A are operated, each of which picks up its share of the stock and moves it to a different position along the length of the tank 10. In other words, if a series of cooks should be admitted to the tank through the inlet 21 and the 95 agitators are operated as described, and each of these cooks varied in consistency and in other properties from all of the other cooks, it follows that as the first cook is admitted to the tank a portion thereof will be picked up by each of the 100 pipes 24 to 28 inclusive, then raised to the upper portion of the tank 10 and discharged laterally to a different portion of the tank from which it was picked up. Obviously, the number 105 of pumps may be varied at will.

It will be noted that in addition to the fact that the pumps 14-A, 15-A and 16-A discharge their pulp forwardly toward the inlet end of the tank at different distances therefrom, that the pump 17-A, which is farther from the end 19 than are the pumps 14-A, 15-A and 16-A, discharges its pulp nearest to the end 19.

The function of the pump 18-A is to prevent the formation of a dead spot in the mass of pulp 10 near the end 22 and to insure, with the remaining units, that every portion of the pulp within the tank will have a uniform or average blend after the pumps have been operated a sufficient length of time, which in no case need be until 15 the pulp is injured by the agitating action. In other words, regardless of variations in properties (which variations are bound to occur in succeeding cooks of pulp) there will be such a complete intermingling of the various portions of all of the 20 cooks which compose the tankful of stock that a complete uniformity is obtained thereby.

In the form of the device shown in Figs. 4 and 5 the tank 37 is upright and its bottom 38 is formed of an annular trough 39 whose central 25 portion 40 is depressed forming a well for a pipe 41 at whose lower end is mounted a pump 42-A which is driven by the motor 42, which pump discharges pulp from the openings 43 over the apron 44. Above the trough 39 are a number 30 of pipes 45 concentrically disposed around the pipe 41. Each pipe 45 has a pump 46-A provided with a motor 46 and the pump discharge passes through a horizontal pipe 47 and through a downturned elbow 48 which opens into the tank 35 top 49 and discharges in the general direction of the next adjacent pipe 45, although somewhat inwardly therefrom.

The intake pipe 50 enters one side of the tank 37 near the top thereof, and the discharge pipe 30 51 leaves the tank 37 near the bottom thereof, preferably opposite the intake 50.

In this form of the device there is a constant transfer of pulp about the tank, not by series circulation as is ordinarily the case, but by elevating the pulp at one point and returning it to the tank at a more or less remote point where it is divided and again picked up by the central pipe 41 and the next outer pipe 45.

Here again we have a complete intermingling 30 of the various streams set up by the pumps employed therein, and while the outward appearance of the two forms of this device is somewhat different there is a strong similarity in their principles of operation.

In the form of the device shown in Figs. 6 and 7 the tank 52 is provided with an upright pipe 53 at the lower end of which is mounted the pump 54. Near the middle of the pipe 53 and well 35 toward the top of the tank is a side outlet pipe 55 provided with a valve 56. The pump 54 is operated by the motor 57 through the shaft 58. On the shaft 58 is also mounted an impeller 59 which is at the upper end of the pipe 53.

It can be seen that any pulp moved upwardly 35 through the pipe 53 by the pump 54 will normally be distributed over the entire area of the tank by the impeller 59. Obviously, if the valve 56 is open stock will flow from the pipe 55 under the head formed by the upper portion of the pipe 53—that is, its portion above the pipe 55.

In this form of the device the usual inlet pipe 60 and the outlet pipe 61 are provided. Either 40 of the pipes 55 or 61 may be used to draw stock from the tank 52. A suitable housing or cage 62 is provided around the impeller 59.

The operation of this form of the device is quite similar to that in the form previously described, except that the column of stock rising through the pipe 53 is distributed laterally in the form of a spray, or in a number of small streams, thereby insuring a complete mixing and blending of the stock. 80

In the form of the device shown in Fig. 8 the pump 63 is provided with a plurality of horizontal suction pipes 64 which are close to the bottom 65 of the tank. The purpose of these suction pipes is to draw the stock which enters the pump from separated points of the tank bottom and the collected lines of stock are mingled by the pump action and then distributed by the 85 impeller 59. In other words, with this form of the device the stock is picked up at remote points, mixed and then distributed to remote points 90 within the tank.

Obviously, any number of upright pipes 53 may 95 be employed with a given tank without departing from the spirit of this invention.

I claim:

1. A pulp mixer consisting of a tank, a plurality of pumps associated with said tank adapted 100 to draw stock from the lower portion thereof at separate points and to return same to said tank between said separated points, and an additional pump having its discharge extending beyond the section zones of several of the first-mentioned 105 pumps.

2. An elongated tank having a series of vertical shaft pumps disposed along the length thereof adapted to raise stock from the bottom of said tank to the upper portion thereof, said tank having inlet and outlet connections at opposite ends thereof, the pumps nearest the inlet end discharging in the direction of said inlet end within a restricted distance from the point of elevation, and a pump remote from said inlet end 115 having an elongated discharge extending beyond several of said pumps and discharging nearest to said inlet end.

3. An elongated tank having a series of vertical shaft pumps disposed along the length thereof 120 adapted to raise stock from the bottom of said tank to the upper portion thereof, said tank having inlet and outlet connections at opposite ends thereof, the pumps nearest the inlet end discharging in the direction of said inlet end within 125 a restricted distance from the point of elevation, a pump remote from said inlet end having an elongated discharge extending beyond several of said pumps and discharging nearest to said inlet end, and a circulating pump at the discharge end 130 of said tank.

4. A method of mixing stock consisting of elevating it from a common body at a series of 135 points, returning it to said body at intermediate points, and causing certain portions of said stock to be transferred from one point to another not immediately adjacent thereto.

5. A pulp mixer consisting of a tank, in combination with an upright riser mounted in said 140 tank, a pump at the bottom of said riser, a laterally discharging impeller at the upper end of said riser, and means for operating said pump and impeller.

6. A pulp mixer consisting of a container having an upright riser therein, means for moving pulp upwardly through said riser and discharging same from the upper end thereof, a laterally discharging impeller at the upper end of said riser, and a pulp take-off pipe connected with said 145 150

riser below its discharge point whereby stock may be drawn from said riser.

7. In a pulp mixer, the combination of a pump having a plurality of spaced inlets, a riser through which pulp can be elevated, a motor for actuating said pump having a shaft extending longitudinally through said riser, and an impeller on said

shaft at the discharge end of said riser whereby stock which has been collected from various portions of a tank may be elevated and mixed at the same time and further mixed and distributed over the area of the stock body from which pulp is being drawn by said pump. 80
